US0D1106218S

(12) **United States Design Patent** (10) **Patent No.:** **US D1,106,218 S**
(45) **Date of Patent:** **** Dec. 16, 2025**

(54) **DATA ACCESSING DEVICE**

(71) Applicant: **Kingston Digital, Inc.**, Fountain Valley, CA (US)

(72) Inventor: **Hui-Hsin Lu**, Hsinchu (TW)

(73) Assignee: **Kingston Digital, Inc.**, Fountain Valley, CA (US)

(**) Term: **15 Years**

(21) Appl. No.: **29/935,304**

(22) Filed: **Apr. 1, 2024**

(51) **LOC (15) Cl.** **14-03**

(52) **U.S. Cl.**

USPC **D14/480.1; D14/435.1**

(58) **Field of Classification Search**

(57) **CLAIM**

The ornamental design for a data accessing device, as shown and described.

DESCRIPTION

FIG. 1 is a perspective view of a data accessing device of the claimed design;

FIG. 2 is another perspective view of FIG. 1;

FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1;

FIG. 8 is a bottom plan view of FIG. 1;

FIG. 9 is a perspective view thereof, showing the device in a usage state; and,

FIG. 10 is another perspective view thereof, showing the device in a usage state.

The dash-dash broken lines in the drawings illustrate portions of the data accessing device that form no part of the claimed design.

1 Claim, 10 Drawing Sheets
